JEWELLED INSERT FOR A CHAIR BACK OR SIMILAR ARTICLE

Robert E. Kjer Jakobsen, Manhattan Beach, Calif., assignor to Virtue Bros. Mfg. Co., Los Angeles, Calif.,
a corporation of California

Filed Oct. 17, 1960, Ser. No. 62,513

Term of patent 14 years

(Cl. D15—1)

FIG. 1 is a front elevational view of my design for a jeweled insert for a chair back or similar article;

FIG. 2 is a top plan view of said band;

FIG. 3 is an end elevational view of said band; and
FIG. 4 is a back elevational view of said band.

The broken line showing in FIG. 1 is for illustrative purposes only.

I claim:

The ornamental design for a jeweled insert for a chair back or similar article, substantially as shown and described.
